PUSH-PULL AMPLIFIER SYSTEM

Benjamin F. Miessner, Short Hills, N. J., assignor, by mesne assignments, to Radio Corporation of America, New York, N. Y., a corporation of Delaware

Application November 8, 1929. Serial No. 405,584

10 Claims. (Cl. 179—171)

My invention relates generally to push-pull amplifier systems and more particularly to means within said system for maintaining a balance between the tubes thereof.

5 The primary object of my invention is to maintain a perfect balance between the tubes of a push-pull amplifier system so that the impedances of the tubes are identical with the resultant equalization of amplification and like 10 effects.

Further objects will become apparent as the description of my invention is developed by reference to the accompanying drawing forming a part of this specification in which

15 Fig. 1 diagrammatically represents one form of push-pull amplifier system in which my invention has been incorporated, and

Fig. 2 diagrammatically illustrates a modification thereof.

20 Referring to the drawings VT₁ and VT₂ designate two electron tubes, the grids of which are connected to the split secondary S₁ of push-pull input transformer IT, the center tap of which is connected to the negative terminal of 25 a source of fluctuating current SF. The plates of the tubes VT₁ and VT₂ are connected to the primary P of the output transformer OT in the usual manner, the midpoint of the primary P being connected to the positive terminal of a 30 source of fluctuating current SF.

In Fig. 1 I have shown the filaments of tubes VT₁ and VT₂ energized from a common source of alternating current through a heating transformer HT, the center tap CT of which is connected through a grid biasing resistance BR to the negative terminal of the source SF. Between one leg of each filament and one terminal of the heating transformer HT, I have provided a potentiometer P₁ the resistance R₁ of which 35 is connected between the respective filaments of VT₁ and VT₂.

In Fig. 2 I have provided two potentiometers P₁ and P₂, the resistances R₁ and R₂ of which are in series in the common connections for the 40 filaments of tubes VT₁ and VT₂. In this instance I have also provided a center tap potentiometer CP, the variable tap of which is connected to the bias resistance BR in lieu of center tap connection CT of Fig. 1.

45 In the operation of Fig. 1, the filament emission and therefore the impedance of the tubes VT₁ and VT₂ may be differentially controlled by varying the movable tap of potentiometer P₁ so that the amplification of each tube may 50 be made to equal that of the other. In this

system, with tubes widely variant in amplification characteristics, however, there may be a slight displacement of the center tap connection CT with respect to the electrical center of the filaments of tubes VT₁ and VT₂. This 60 objection I have eliminated in the connection shown in Fig. 2. In the structure of this figure, variable taps of potentiometers P₁ and P₂ may be varied in a manner similar to that of the one potentiometer P₁ of Fig. 1. If these potentiometers are varied equally as by a uni-control of the two movable elements, there will be no displacement of the center tap for the filament system. However, if it is not desired to have uni-control of potentiometers P₁ and P₂ 70 the electrical center of each of the filaments may be obtained by varying the movable tap of the center tap potentiometer CP. It is to be understood that the center tap potentiometer CP may also be used in lieu of the center tap connection CT of Fig. 1 without departing from the spirit of my invention.

75 While I have described my invention as embodied in certain specific circuits, it is to be understood that various modifications thereof 80 will be apparent to those skilled in the art without departing from the spirit of my invention as defined by the scope of the claims appended hereto.

Having thus described my invention, what I 85 claim is:

1. In an amplifier system, the combination of a pair of electron tubes, push-pull input and output circuits therefor, a resistance common to said input and output circuits for determining the 90 biasing of said tubes, said tubes having a common filament energizing system connected to a source of alternating current, the filaments of said tubes being connected in parallel in said system, and a potentiometer, the resistance of which is series connected between corresponding legs of the filament of each tube and the variable tap of which is connected to one terminal of said energizing system, the other terminal of said energizing system being connected to the other corresponding legs of the filament of each tube, whereby the impedance of said tubes may be differentially varied.

2. In an amplifier system, the combination of a pair of electron tubes, push-pull input and output circuits therefor, said tubes having a common filament energizing system connected to a source of alternating current, the filaments of said tubes being connected in parallel in said system, and a plurality of potentiometers the resistances of which are series connected between 100 105 110

- corresponding legs of said filament and the variable taps of which are connected to the terminals of said energizing system, whereby the impedances of said tubes may be differentially varied. 5

3. In an amplifier system, the combination of a pair of electron tubes, push-pull input and output circuits therefor, said tubes having a common filament energizing system connected to a source of alternating current, the filaments of said tubes being connected in parallel in said system, a plurality of potentiometers the resistances of which are series connected between corresponding legs of said filament and the variable taps of which are connected to said energizing system, whereby the impedances of said tubes may be differentially varied, and a common means for obtaining the electrical center of both of said filaments. 10

4. In an amplifier system, the combination of a pair of electron tubes, push-pull input and output circuits therefor, said tubes having a common filament energizing system connected to a source of alternating current, the filaments of said tubes being connected in parallel in said system, a plurality of potentiometers the resistances of which are series connected between corresponding legs of said filament and the variable taps of which are connected to said energizing system, whereby the impedances of said tubes may be differentially varied, and a common grid return connection from the center of said push-pull input circuit to the electrical center of both of said filaments. 15

5. In an amplifier system, the combination of a pair of electron tubes, push-pull input and output circuits therefor, said tubes having a common filament energizing system connected to a source of alternating current, the filaments of said tubes being connected in parallel in said system, a plurality of potentiometers the resistances of which are series connected between corresponding legs of said filament and the variable taps of which are connected to said energizing system, whereby the impedances of said tubes may be differentially varied, and a common grid return connection from the center of said push-pull input circuit to the electrical center of both of said filaments, said connection including a potential developing element for determining the grid bias of said tubes. 20

6. In an amplifier system, the combination of a pair of electron tubes, push-pull input and output circuits therefor, said tubes having a common filament energizing system connected to a source of alternating current, the filaments of said tubes being connected in parallel, a plurality of potentiometers the resistances of which are series connected between corresponding legs of said filament and the variable taps of which are connected to said energizing system, whereby the impedances of said tubes may be differentially varied, and a common grid return connection from the center of said push-pull input circuit to the electrical center of both of said filaments, said connection including a resistance whereby the combined plate current of said tubes determines the grid bias for each of said tubes. 25

7. In an amplifier system, the combination of a pair of electron tubes, push-pull input and output circuits therefor, said tubes having a common filament energizing system connected to a source of alternating current, the filaments of said tubes being connected in parallel in said system, and a plurality of potentiometers the resistances of which are series connected between corresponding legs of said filament and the variable taps of which are connected to said energizing system, whereby the impedances of said tubes may be differentially varied, a resistance shunted across the terminals of said energizing system and a connection including a resistance between an intermediate point of said shunted resistance and a point in said input circuit. 30

8. In an amplifier system, a pair of electron discharge devices arranged in push-pull relationship comprising an input circuit including the secondary winding of a transformer, and an output circuit including the primary winding of a transformer, said discharge devices having a common filament energizing system connected to a source of current, the filaments of said devices being connected in parallel in said system, and a pair of resistances in series each thereof connected respectively between the corresponding legs of said filaments, a variable connection between a point on one of said resistances and a terminal of said filament energizing system and a connection between a point on the other of said resistances and the other terminal of said filament energizing system, a resistance shunted across the two terminals of said filament energizing system, a connection including a resistance between a point on said shunting resistance and a point on said secondary winding and a connection including a source of energy, between the secondary winding end of said last named resistance and a point on said primary winding. 35

9. In an amplifier system a pair of electron discharge devices arranged in push-pull relationship including an input circuit having the secondary winding of a transformer, and an output having the primary winding of a transformer, said discharge devices having a common filament energizing system connected to a source of energizing current, the filaments of said devices being connected in parallel in said last-named system, a resistance in series between corresponding legs of the filament of each discharge device, a variable connection between a point on said resistance and a terminal of said filament energizing system and a connection between the other terminal of said filament energizing system and a point common to the other corresponding legs of said filaments, a resistance shunted across the two terminals of said filament energizing system, a connection including a biasing resistance between a point on said shunting resistance and a point on said secondary winding and a connection including a source of energy between the secondary winding end of said biasing resistance and a point on said primary winding. 40

10. In an amplifier system the combination of a pair of electron tubes, push-pull input and output circuits therefor, said tubes having a common filament energizing system connected to a source of alternating current, the filaments of said tubes being connected in parallel in said system, a resistance in series between corresponding legs of the filament of each tube, a variable connection between a point on said resistance and a terminal of said filament energizing system and a connection between the other terminal of said filament energizing system and a point common to the other corresponding legs of said filaments, an impedance effectively connected across said source of alter- 45

inating current and said filaments, a common grid return connection from the center of said push-pull input circuit to a point of said impedance, said connection including a potential developing element for determining the operating characteristics of said tubes, a common plate return connection from the center of said push-pull output circuit to said same point of said impedance, said last named connection includ-

ing a source of uni-directional fluctuating plate current and said potential developing element in series, and means for variably disposing said common connection to said impedance to allow for adjusting said common connection to a point of said impedance to produce equalized effects in the outputs of both tubes.
